W. B. LUCAS

COMBINATION PNEUMATIC JACK AND TIRE INFLATER

Filed Sept. 6, 1921

UNITED STATES PATENT OFFICE.

WILLIAM B. LUCAS, OF OAK PARK, ILLINOIS.

COMBINATION PNEUMATIC JACK AND TIRE INFLATER.

Application filed September 6, 1921. Serial No. 498,685.

To all whom it may concern:

Be it known that I, WILLIAM B. LUCAS, a citizen of the United States of America, and a resident of Oak Park, county of Cook, and 5 State of Illinois, have invented certain new and useful Improvements in Combination Pneumatic Jacks and Tire Inflaters, of which the following is a specification.

This invention relates to automobile accessories and especially to means for raising the vehicle axle and to means for inflating the tires.

The main objects of the invention are to provide a simplified form of jack adapted 15 for automatic operation; to provide such a device of compact form and of light weight; to provide a jack of the character stated adapted for manufacture at a low cost and of few parts adapted for permanence and 20 simplicity of operation.

An illustrative embodiment of this invention is shown in the accompanying drawings, in which—

Figure 1 is a vertical sectional view of one 25 embodiment of the invention adapted to serve either as a jack or a tire inflater.

Figure 2 is a vertical section of another embodiment.

In the construction shown in Figure 1, the 30 jack comprises a pair of relatively movable interfitting members 1 and 2 disposed in mutually expansible relation. The frame part 1 is cylindrical and the chamber there- 35 of contains a piston-like head 3 secured to the inner end of the member 2. The upper end of the member 1 is provided with a guide part 4 to retain the piston member 2 in concentric position relative to the member 1 when the jack is used.

40 The body or shaft of piston member 2 is hollow and the closed chamber thereof is adapted to contain, under high pressure, a fluid of normally gaseous character in liquid form.

45 A tube 5 is provided for admitting charges of fluid successively from the storage chamber in part 2 to the expansion chamber in part 1. The flow of fluid through said tube is controlled by a manually-controlled valve 6, and the release of fluid from the expansion chamber is controlled by a separate valve 7, preferably in the form of a spring closed needle valve which may be opened by downward pressure with the hand as under- 50 stood in the art. The valve 6 is also of the

needle type, so as to readily permit of very gradual opening.

Whenever it is desired to use this device for inflating a tire, the lower end of tube 5 is disconnected at the point 8 from the jack 60 and connected to the nipple 9 of the tire 10 whereupon fluid may be admitted from the supply chamber by opening the valve 6.

The operation of the jack is as follows: The jack is placed in upright position on the 65 ground and the head 11 is placed under the axle 12, the tube 5 being connected as shown by full lines in Figure 1. The valve 6 is then opened sufficiently to charge the expansion chamber in frame 1 and thereby lift the 70 piston 2 and the load 12 carried thereby. When the load 12 is to be lowered, the operator presses his finger downwardly upon the projecting stem of valve 7.

In the construction in Figure 2 the jack 75 is entirely self-contained, the chamber connecting means being inside the jack as indicated at 13. Moreover a modified form of valve is provided at 14 to regulate the flow of gas into and downward through tube 13. 80 The upper wall 4 of the frame or base part 1 is provided with vent openings 15 to prevent pressure developing above the piston head 3. Otherwise, than as above explained, the structure and operation of the two em- 85 bodiments shown are substantially alike, except that a separate filling cock 16 is provided on Figure 2. In Figure 1 the storage chamber is filled by connecting a supply tube at 17 in place of tube 5.

90 A relatively light-weight jack, weighing for instance about five pounds, may be charged from time to time with a sufficient quantity of liquid carbon dioxide to operate the jack at least fifty times or to inflate a dozen tires or more. The cost of recharging the storage chamber at the usual commercial rate for carbon dioxide is about ten cents. The many advantages of this device are ap- 95 parent, particularly its simplicity and low cost, its ease of operation, its strength and quickness of operation and its low cost both for construction and maintenance in use.

100 Although but two specific embodiments of this invention are herein shown and de- 105 scribed, it will be understood that numerous details of the constructions shown may be altered or omitted without departing from the spirit of this invention as defined by the following claim.

I claim:

A combination jack and tire inflater having a high pressure storage chamber to contain a normally gaseous fluid in liquid form under high pressure, an expansion chamber arranged to receive fluid from said storage chamber to operate said jack and a tubular

connection having one end communicating with said storage chamber and its other end being interchangeable with respect to said expansion chamber and a tire to be inflated.

Signed at Chicago this 26th day of August, 1921.

WILLIAM B. LUCAS.
